US00D893508S

(12) **United States Design Patent** (10) Patent No.: **US D893,508 S**
Laska et al. (45) Date of Patent: **** Aug. 18, 2020**

(54) **DISPLAY SCREEN OR PORTION THEREOF WITH GRAPHICAL USER INTERFACE**(71) Applicant: **GOOGLE INC.**, Mountain View, CA (US)(72) Inventors: **Jason N. Laska**, San Francisco, CA (US); **Melissa McLean**, Novato, CA (US)(73) Assignee: **GOOGLE LLC**, Mountain View, CA (US)(**) Term: **15 Years**(21) Appl. No.: **29/593,971**(22) Filed: **Feb. 14, 2017****Related U.S. Application Data**

(63) Continuation of application No. 29/504,605, filed on Oct. 7, 2014, now Pat. No. Des. 782,495.

(51) **LOC (12) Cl.** ..... **14-04**(52) **U.S. Cl.**USPC ..... **D14/485**(58) **Field of Classification Search**USPC D14/485-495

Primary Examiner — Daniel J Domino(74) *Attorney, Agent, or Firm* — Morgan, Lewis & Bockius LLP(57) **CLAIM**

The ornamental design for a display screen or portion thereof with graphical user interface, as shown and described.

DESCRIPTION

FIG. 1 is front view of a first embodiment of a display screen or portion thereof with graphical user interface showing the new design; and,

FIG. 2 is a front view of a second embodiment thereof. The broken lines shown in the drawings represent portions of the display screen or portion thereof with graphical user interface that form no part of the claimed design.

1 Claim, 2 Drawing Sheets# US D893,508 S
